REFRIGERATOR EVAPORATOR

Leonard W. Atchison, Schenectady, N. Y., assignor to General Electric Company, a corporation of New York

Application September 20, 1934, Serial No. 744,794

13 Claims. (Cl. 62—126)

My invention relates to flooded type evaporators for refrigerating systems.

Flooded type evaporators comprise a chamber containing a body of liquid vaporizable refrigerant and the liquid refrigerant is vaporized in the chamber upon the absorption of heat from the body to be cooled. It has been found in practice that the temperature of the liquid refrigerant in the evaporator must rise several degrees above the boiling point thereof, at the pressure existing in the evaporator before vaporization, or boiling, is started below the surface of the liquid. This phenomena is commonly known as superheating of the liquid. It is, of course, desirable to avoid this superheating, both in order to increase the efficiency of the machine and to improve the accuracy of control of the temperature of the evaporator.

It is an object of my invention to provide a flooded evaporator for refrigerating systems in which boiling or vaporization of the liquid refrigerant contained therein will be initiated without substantial superheating thereof, and in which vaporization of the liquid refrigerant will be initiated in such manner as to promote rapid circulation of the liquid refrigerant in the evaporator.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a perspective view of a refrigerating system including an evaporator embodying my invention; Fig. 2 is a detailed sectional view of a portion of the evaporator shown in Fig. 1; Fig. 3 is a perspective view of a modified form of evaporator embodying my invention; Fig. 4 is a detailed view of a portion of the evaporator shown in Fig. 3; and Fig. 5 is a detailed view of a modified form of the evaporator shown in Fig. 3.

Referring to the drawing, in Fig. 1, I have shown a refrigerating system including an evaporator embodying my invention. In this system a motor and a compressor are arranged in a hermetically sealed casing 10. Gaseous refrigerant is compressed by the motor driven compressor in casing 10 and is discharged into a condenser 11 where it is liquefied. The liquefied refrigerant flows from the condenser 11 through a flow controlling float valve 12 into a liquid line 13 which injects liquid refrigerant into an evaporator 14. The evaporator 14 comprises two sheets of metal 15 and 16. Sinuous indentations 18 and 19 are formed in the sheet 15 which cooperate with sheet 16 to define refrigerant passages extending

across the walls of the evaporator 14, the adjacent ends of the sinuous passages 18 and 19 being connected by a plurality of ducts 20. The sheet 16 is preferably slightly larger than the sheet 15 and its edges are folded over the adjacent edges of sheet 15. The sheets are welded or otherwise secured together along the edges and between the refrigerant passages and the sheets are then bent so as to have an inverted L-shaped form, thus providing a freezing shelf 18a upon which freezing trays or other articles may be conveniently supported within a refrigerator cabinet in which the evaporator is used.

In order to flood the evaporator 14 with liquid refrigerant and remove vaporized refrigerant therefrom, I provide a spherical header 21 having a depending cylindrical portion 22. The lower portion of the spherical header is connected by conduit 23 to the upper end of the sinuous passage 18 in the shelf 18a, and the cylindrical portion 22 is connected by a conduit 24 to the sinuous passage 19 in the evaporator at the lowermost bend therein. The header 21 is maintained about half full of liquid refrigerant, the level of the liquid refrigerant therein being above the shelf 18a of the evaporator in order to flood the evaporator.

Liquid refrigerant is injected at 13a from liquid line 13 into the end of one of the horizontal portions of the sinuous refrigerant passage 19, which induces a flow of liquid refrigerant through the sinuous passage 19, ducts 20, sinuous passage 18, and the connection 23 to a header 21, the liquid refrigerant returning to the evaporator 14 through the connection 24 to the sinuous passage 19 of the evaporator. In this manner the injection of the liquid refrigerant at 13a into the evaporator 14 induces rapid circulation of liquid refrigerant therefrom through the header 21 and refrigerant vaporized by the absorption of heat is quickly carried to the header where it rises above the liquid level therein and is withdrawn from the header through the suction conduit 25 by the compressor within the casing 10. This suction conduit 25 extends above the level of liquid refrigerant in the header 21, so as to withdraw vaporized refrigerant without withdrawing liquid refrigerant therefrom. The foregoing described refrigerating machine construction is not my invention, but is the invention of Christian Steenstrup, and is described and claimed in his application Serial No. 733,044, filed June 29, 1934, and assigned to the General Electric Company, assignee of this application.

It will be noted that the lower leg of the sinuous passage 19 is not in the direct path of refrigerant circulation described above, so that vaporization of liquid refrigerant is retarded and superheating of the liquid refrigerant occurs therein. In accordance with my invention I have

modified the construction of this lower leg of sinuous passage 19 in order to facilitate the initiation of vaporization of liquid refrigerant therein to avoid superheating of the liquid refrigerant and to promote rapid circulation of refrigerant therethrough. As best shown in Fig. 2, I do this by providing an indentation 26 in the upper wall of the lower leg of the sinuous passage 19 near the closed end 27 thereof. A body 10 of vaporized refrigerant 28 is trapped between the indentation 26 and closed end 27 by the liquid refrigerant 29 which normally fills the sinuous passage 19. In this way, a body of vaporized refrigerant is provided below the upper level of 15 liquid refrigerant in the evaporator and in contact with an unbroken free surface 30 of liquid refrigerant. I have found that liquid refrigerant will vaporize much more easily from a surface exposed to a vapor than a surface exposed to the 20 wall of a passage. As a consequence, vaporization of the liquid refrigerant 29 is facilitated on the exposed surface 30 and vaporization begins in the evaporator without substantial superheating. The bubbles of vaporized refrigerant formed on 25 the surface 30 move along the lower leg of sinuous passage 19 of evaporator 14 and pass upwardly through sinuous passage 19 to the point 13a where they are entrained by the entering liquid refrigerant. This movement of bubbles of 30 vaporized refrigerant through the lower portion of sinuous passage 19 sets up a rapid circulation of refrigerant therein and aids in the recirculation of liquid refrigerant from the conduit 24.

Another form of evaporator embodying my invention is shown in Fig. 3. This evaporator includes a horizontal cylindrical header 31 and depending reentrant passages 32 connected thereto. Liquid refrigerant is supplied to the header 31 through liquid line 33 and flows from the header 40 through the passages 32, the header 31 being maintained about half full of liquid refrigerant thus flooding the passages 32. Freezing trays or other articles to be cooled may be conveniently supported in the evaporator. As the 45 liquid refrigerant contained in the passages absorbs heat bubbles of vaporized refrigerant are formed in the passages 32 and rise to the header 31 causing circulation of liquid refrigerant from the header 31 through the passages 32, the direction of circulation being ordinarily upward on the 50 side of the evaporator which is at the highest temperature. This circulation of liquid refrigerant quickly carries refrigerant vaporized by the absorption of heat to the header 31, where it rises 55 above the liquid level therein and is drawn off through suction line 34.

In accordance with my invention the construction of the passages 32 has been modified to facilitate the initiation of vaporization of liquid refrigerant therein without substantial superheating and to promote rapid circulation of refrigerant therethrough. As best shown in Fig. 4, I do this by providing grooved plates 35 with flattened ends 36 which are welded or otherwise fastened 60 to the interior walls of the passages 32, the open ends of the grooves being directed downwardly to form vapor pockets or traps 35a. The grooved plates 35 may be provided in any or all of the 65 passages 32. In Fig. 3 they are shown as being placed in all except the end passages. A body of vaporized refrigerant 37 is confined by each of the grooved plates 35 below the upper level of the liquid refrigerant in the header 31, being in contact with the free surfaces 38 of the liquid refrigerant. As described above, this surface of

liquid refrigerant exposed to vaporized refrigerant within the traps 35a facilitates the ebullition or vaporization of refrigerant below the surface of the main body thereof. When the temperature of the liquid refrigerant is raised to its boiling point, bubbles of vaporized refrigerant are formed at the surfaces 38 in the pockets 35a, escape below the pockets, and bubble up through the passages 32. It is advantageous to place the pockets 35a in the side of the passages 32 adjacent the highest ambient temperature for in this way the bubbles of refrigerant formed at the surface 38 help to promote the circulation of liquid refrigerant induced by the vaporization of refrigerant throughout the passages 32.

In Fig. 5 I have shown an alternative form of refrigerant vapor pocket which may be used in such an evaporator as that shown in Fig. 3. This vapor pocket is formed by utilizing inverted cups 39 which are secured to the upper interior wall of the passages 32 in the lower horizontal portions thereof. The cups 39 contain bodies of vaporized liquid refrigerant 40 which are exposed to free surfaces 41 of the liquid refrigerant contained in the passages 32. I prefer to place the 25 cups 39 on the side of the center line of the passages 32 which is nearest the highest ambient temperature in order to aid circulation of liquid refrigerant through the evaporator, induced in the main portion of the passages by the vaporization of liquid refrigerant.

It will be apparent to those skilled in the art that other forms of pockets or traps may be provided to confine a body of vaporized refrigerant below the surface of the liquid refrigerant in an evaporator, in which the vaporized refrigerant in the pockets is in contact with a surface of substantial area of liquid refrigerant in order to promote boiling or vaporization of the liquid refrigerant without substantial superheating there- 40 of.

While I have shown a particular embodiment of my invention in connection with evaporators of compression refrigerating machines, I do not desire my invention to be limited to the particular construction shown and described, and I intend in the appended claims to cover all modifications within the spirit and scope of my invention.

What I claim as new and desire to secure by 50 Letters Patent of the United States, is:—

1. An evaporator of the flooded type for refrigerating apparatus containing a body of vaporizable liquid refrigerant, and means for initiating vaporization of said body of liquid refrigerant, 55 said means providing a body of vaporized refrigerant exposed to a free surface of said liquid refrigerant and retained thereby below a portion of said body of liquid refrigerant.

2. An evaporator of the flooded type for refrigerating apparatus containing a quantity of vaporizable liquid refrigerant, and means for initiating vaporization of said liquid refrigerant, 60 said means providing a body of vaporized refrigerant confined below the upper surface of said liquid refrigerant in contact with an unbroken free surface thereof of substantial area.

3. An evaporator for refrigerating apparatus of the flooded type including a header and a refrigerant containing portion connected thereto 70 below the normal liquid level in said header, said header and said refrigerant containing portion containing a body of vaporizable liquid refrigerant, and means for initiating vaporization of said body of liquid refrigerant, said means providing 75

a body of vaporized refrigerant exposed to a free surface of said liquid refrigerant and retained thereby below a portion of said body of liquid refrigerant below the upper surface thereof for inducing circulation of said liquid refrigerant through said passagé.

5 4. An evaporator for refrigerating apparatus of
the flooded type including a header and a passage
connected thereto having a portion thereof below
the normal liquid level in said header, said head-
er and passage containing a body of vaporizable
10 liquid refrigerant, and means including a con-
stricted section in said passage trapping a body of
vaporized refrigerant in said passage in contact
with a free surface of said liquid refrigerant be-
15 low the upper surface thereof to initiate vaporiza-
tion of said liquid refrigerant.

5 of the flooded type including a header and a re-
entrant passage connected thereto having a por-
tion thereof below the normal liquid level in said
header, said header and passage containing a
body of vaporizable liquid refrigerant, and means
for aiding the circulation of said liquid refrig-
erant through said passage produced by vapor-
ization of refrigerant therein, said means includ-
ing means in the section of said passage adjacent
the highest ambient temperature for confining a
body of vaporized refrigerant in said passage in
15

15 5. An evaporator for refrigerating apparatus of
the flooded type including a header and a reen-
trant passage connected thereto having a portion
below the normal liquid level in said header, a
20 non-entrant passage connected to said first
mentioned passage and provided with a closed
outer end, said header and passages containing
a body of vaporizable liquid refrigerant, and
means including a constricted section in said
25 non-entrant passage adjacent said closed end
thereof trapping a body of vaporized refrigerant
between said constricted section and said closed
outer end in contact with a free surface of said
liquid refrigerant below the upper surface there-
30 of for inducing circulation of said liquid refriger-
ant through said non-entrant passage.

15 contact with a free surface of said liquid refriger-
ant below the upper surface thereof.

20 10. An evaporator for refrigerating apparatus
of the flooded type including a header and a re-
entrant passage connected thereto having a por-
tion thereof below the normal liquid level in said
header, a body of vaporizable liquid refrigerant,
25 and means for inducing circulation of said liquid
refrigerant through said passage, said means in-
cluding a grooved metallic member having a
closed upper end secured to a vertical interior
wall of said passage for confining a body of vapor-
30 ized refrigerant in contact with a free surface of
said liquid refrigerant below the upper surface
thereof.

15 11. An evaporator for refrigerating apparatus
20

55 7. An evaporator for refrigerating apparatus of the flooded type including a header and a re-entrant passage connected thereto having a por-
tion thereof below the normal liquid level in said header, a non-reentrant passage connected to said header, said header and passages containing a body of vaporizable liquid refrigerant, an inlet connection provided with an injector in said re-
entrant passage for inducing circulation of said liquid refrigerant therethrough from said header, and means confining a body of vaporized refrigerant in said non-reentrant passage in contact with a free surface of said liquid refrigerant be-
60 low the upper surface thereof for inducing circu-
lation of said liquid refrigerant through said non-
reentrant passage.

65 for inducing circulation of said liquid refrigerant through said passage, said means including an inverted cup secured to an interior wall of said passage adjacent the lowermost portion thereof for confining a body of vaporized refrigerant in contact with a free surface of said liquid refrigerant below the upper surface thereof.

60 13. An evaporator for refrigerating apparatus of the flooded type including a header and a re-entrant passage connected thereto having a por-
tion thereof below the normal liquid level in said header, said header and passage containing a body of vaporizable liquid refrigerant, and means for aiding the circulation of said liquid refrigerant through said passage induced by the vaporization of liquid refrigerant therein, said

65

70 8. An evaporator for refrigerating apparatus of the flooded type including a header and a re-entrant passage connected thereto having a portion thereof below the normal liquid level in said header, said header and passage containing a body of vaporizable liquid refrigerant, and means 75 confining a body of vaporized refrigerant in said duct in contact with a free surface of said liquid means including an inverted cup for confining a body of vaporized refrigerant in contact with a free surface of said liquid refrigerant below the upper surface thereof, said cup being secured to an interior wall of said passage and displaced from the center thereof to the side adjacent the highest ambient temperature.

LEONARD W. ATCHISON. 75
